(57) **CLAIM**

The ornamental design for transparent controls for vehicles as shown and described.

DESCRIPTION

FIG. 1 is a front view of a first embodiment of a transparent control for vehicles of our present design, showing a transparent portion along a top thereof;

FIG. 2 is a rear view thereof, showing the transparent portion along the top thereof;

FIG. 3 is a left side view thereof, showing through the transparent portion along the top thereof;

FIG. 4 is a right side view thereof, showing the transparent portion along the top thereof;

FIG. 5 is a top view thereof, showing through the transparent portion along the top thereof;

FIG. 6 is a bottom view thereof;

FIG. 7 is a top right front perspective view thereof, showing through the transparent portion along the top thereof;

FIG. 8 is a front view of a second embodiment of a transparent control for vehicles of our present design, showing a transparent portion along a top thereof;

FIG. 9 is a rear view thereof, showing the transparent portion along the top thereof;

FIG. 10 is a left side view thereof, showing the transparent portion along the top thereof;

FIG. 11 is a right side view thereof, showing through the transparent portion along the top thereof;

FIG. 12 is a top view thereof, showing through the transparent portion along the top thereof;

FIG. 13 is a bottom view thereof; and,

FIG. 14 is a top right front perspective view thereof, showing through the transparent portion along the top thereof.
